AUSTRALIA.

BALING TANK OR BUCKET.

1,309,652.

Specification of Letters Patent. Patented July 15, 1919.

Application filed December 1, 1917. Serial No. 204,845.

To all whom it may concern:

Be it known that I, ASKIN MORRISON NICHOLAS, a subject of the King of Great Britain, residing at Block 14, Torrington, 5 Bismuth, via Deepwater, in the State of New South Wales, Commonwealth of Australia, have invented certain new and useful Improvements in Baling Tanks or Buckets, of which the following is a specification.

10 This invention relates to baling tanks or buckets, such as are used in excavating work to remove water which collects at the bottom of a shaft or other excavation, more particularly to tanks which are lowered into 15 the shaft, filled there by suction exerted through a suction or vacuum pipe, and then raised to the surface to be emptied.

The purpose of this invention is to provide a tank of this character which will be 20 simple in construction and operation, avoiding the use of inlet valves, and therefore practically foolproof, and which will eliminate the danger to the life of the men working in the shaft, resulting from the breaking 25 away of the pipes due to the premature hauling up of the tank through error on the part of the engineer operating the winding engine. This result is obtained by providing 30 means whereby the suction pipe is held in operative position on the tank through the medium of the suction exerted in the tank through said pipe. By the use of this same means not only will the suction be cut off automatically from the tank, but the actual 35 connection between the suction pipe and the tank is broken, when the tank has been filled. A special advantage of this feature of my invention is the fact that an ordinary 40 ejector, such as a Penberthy, can be used in connection with my improved tank, thus avoiding the use of expensive pumps. Another feature of the invention is the provision of simple means for emptying the 45 tank. All the advantages of my invention will be made clear in the description following hereinafter, and the novel features will be pointed out in the appended claims.

Two embodiments of my invention have been shown in the accompanying drawings, 50 in which—

Figure 1 is a side elevation of my improved tank, with parts in section;

Fig. 2 is a front elevation, with parts in section on line 2—2 of Fig. 1;

55 Fig. 3 is a top view;

Fig. 4 is a detail section through the suction pad and suction pipe used in connection with my invention; and

Fig. 5 is an elevation showing a modified form of my invention, some parts having 60 been omitted from this view.

As an example, I have shown in the drawings a tank or casing of rectangular cross section having side walls 10 and a bottom 11 rigidly connected as by riveting or otherwise, while the cover or lid 12 is preferably connected with the sides removably, to facilitate inspection and repairs, by means of screws 12' screwing into a preferably wooden frame 12'' secured to the inside of 70 the tank, adjacent its top, by means of screws 12*. This frame forms a bearing surface for the lid or cover, and a gasket 12^a of rubber or other suitable material is preferably interposed between the cover plate 75 and the bearing frame, in order to insure an airtight joint.

For the purpose of conveniently lowering and elevating the tank, an iron strap or band 13 is secured to two opposed side walls, 80 this band passing under the bottom from one side wall to the other, and its two ends being held together above the tank and at a distance therefrom by means of a screw bolt 14 which also passes through a link 15 to which 85 will be attached the customary hook of the crane or derrick cable or other hoisting device (not shown). The two strap or band portions are held apart immediately above the tank by a spacing bar 13', in order to 90 prevent undue strain on the sides of the tank when the latter is being lifted. To each of two opposed side walls 11 (preferably those which carry the band 13) is secured a pair of L-shaped guiding brackets 95 16, by means of which the tank is guided in its upward or downward travel along the customary guides or skids 17 supported on the sides of the shaft.

Through the bottom 11 extends an intake 100 pipe 18 whose upper end flares slightly and terminates preferably near the top of the tank, a bracket 18' secured to the inside of the tank holding this pipe in proper position. To the lower end of the pipe 18 is 105 connected a rubber hose 18'' the other end of which is adapted to be immersed into the water or other liquid or material which is to be drawn into the tank.

At a point located preferably near the 110

top of the tank, one of the side walls has a suction opening 19 with which registers normally (that is, during the sucking or pumping operation) a suction pipe consisting preferably of a short piece of iron pipe 20 to which is attached a flexible hose 20' (say, of rubber), which in turn connects with a pipe 20'' leading to the engine room. To the free end of the pipe portion 20 is secured a suction pad consisting preferably of a wooden disk 21 to which is attached on the side toward the inlet end of the suction pipe, a disk 21' of flexible material, for instance rubber or leather. The flat surface of this disk is of considerably larger area than the cross section of the pipe passage. The pipe 20, 20', 20'' may be connected in the engine room with an ordinary ejector.

When it is desired to fill the tank, the intake pipe 18'' having been immersed into the water or other material to be elevated, the suction pad 21, 21' is pressed against the side of the tank, so that the suction pipe will register with the opening 19. The vacuum being immediately created in the tank will draw water or other material through the intake pipe 18'', 18, into the tank, which latter will be filled rapidly. The vacuum will also draw the air from between the flexible portion of the suction pad and the adjacent portion of the tank and will thus hold the pad firmly against the tank wall and establish an air-tight connection between the suction pipe and the tank. The difference of pressure between the atmospheric pressure acting on the outside of the suction pad and the vacuum inside is sufficient to overcome the weight of the pad and the pipe connected with it, and will hold the pad firmly against the tank wall.

As soon as the water level in the tank reaches the suction opening 19, water will be sucked into the suction pipe 20, 20'. The impact of the intrushing water against the curved portion of the pipe will tend to pull the suction pad away from the tank; if this impact, however, should not be sufficient to accomplish this, the weight of the filled suction pipe will pull the pad away. The suction will thus be cut off from the tank automatically. The changed conditions will be noticed immediately in the engine room, and the dropping off of the suction pad will therefore at the same time give a signal to the engineer to stop the ejector or pumping action and to hoist the tank for the purpose of emptying it.

This emptying is done in the following manner: As shown in Figs. 1 to 3, the tank is provided at its lower portion with an opening 10' normally closed by a door 22 secured to the outside wall 10 by means of hinges 10''. On its inner face, this door has a lug 22' to which is pivotally connected

one end of a Z-shaped lever 23 fulcrumed at 24 on the inside of the tank, the other end of this lever being connected pivotally with a rod 25. This rod 25 is connected pivotally with one end of a short lever 26 secured rigidly to a shaft 27 extending through the tank, from one side wall to the other and supported in bearings 28 attached to the outer faces of the respective side walls. On its outer portions, the shaft 27 carries, rigidly connected therewith, handles 29 by means of which a turning movement can be given to the shaft 27. To the shaft 27 are also secured rigidly, two L-shaped levers 26', the free ends of these levers being connected with C-shaped springs 30 secured to the sides of the tank and properly spaced therefrom by short collars 31. It will be seen that the springs 30 tend to press the levers 26' downward (Fig. 1) and consequently the lever 26 mounted on the same shaft, upward, thus exerting an upward pull on the rod 25; this will, by means of the lever 23, hold the door 22 tightly on its seat. In order to open the door for the purpose of discharging the water or other material contained in the tank, one or both of the levers 29 are pressed downward against the action of the springs 30, when the tank in its travel up the shaft, meets the usual stop or dummy. This action will give a downward push to the rod 25 and swing the door open, as indicated in dotted lines in Fig. 1. After the tank has been emptied, the springs 30 will again close the door 22. It will be seen that the connection between the lever 23 and the door 22 is a somewhat loose one, so as to prevent binding of the parts.

A modified form of door and its mechanism is illustrated in Fig. 5. In this construction the door 22'', which opens inwardly, is connected with a rod 25' which in turn connects with a lever 26'' rigidly secured to the shaft 27. To hold the door tightly on its seat, the former is provided with an outwardly-projecting lug 32 having an opening through which a latch or bolt 33 can be passed; this bolt is of sufficient length to project beyond the two side edges of the opening 10', so as to lock the door securely against accidental opening. In order to discharge the contents of the tank, the bolt 33 is first withdrawn, whereupon the door will be opened automatically, as described above in connection with the form of my invention shown in Figs. 1 to 3 inclusive.

To remove sand or other sediments which may have collected in the bottom of the tank, the door 22 or 22'' is opened and a blast of compressed air or steam admitted through the suction opening 19, thus blowing such sediments out through the opening 10'.

As pointed out above, there is a great advantage in the use of a baling tank in com-

bination with a suction pad for establishing communication between the suction pipe and the tank, in view of the fact that this communication will be interrupted instantly 5 and automatically, immediately after the water has reached the suction opening. The danger to the life of the men working in the shaft, due to the possibility of the engineer's pulling away before the tank 10 is full, is entirely eliminated, as such action would simply disconnect the tank from the vacuum, and no harm would result. Furthermore, all that the workmen in the shaft have to do with the tank is to apply the 15 suction pad, after the tank has been lowered into the shaft. The cutting off of the suction from the tank, when the latter is full, the hoisting of the filled tank, and the lowering of the emptied tank, will be attended to from the engine room without 20 requiring any further attention on the part of the men working in the shaft.

While I have described my invention in connection with a baling tank or water- 25 hoisting device, it is evident that it is capable of other uses. Various changes and modifications may also be made without departing from the nature of my invention, as set forth in the appended claims.

30 I claim:

1. A suction tank provided with an outlet communicating with the upper portion of the tank, and having a flat external seating surface, a suction pipe, and a pad secured to the inlet end of said pipe and 35

having a flat surface perpendicular to the axis of said inlet end and adapted for an airtight engagement with said seating surface.

2. A suction tank provided with an outlet 40 communicating with the upper portion of the tank, and having a flat external seating surface, a suction pipe, and a pad secured to the inlet end of said pipe and having a flat surface perpendicular to the axis 45 of said inlet end and adapted for an airtight engagement with said seating surface, the flat surface of the pad being of considerably larger area than the cross section of the pipe passage at the inlet. 50

3. A suction tank provided with an outlet communicating with the upper portion of the tank, and having an external seating surface, a suction pipe, and a pad having a joint-forming surface adapted to engage 55 said seating surface and also having a surface opposite to said joint-forming surface and exposed to the surrounding air when the pad is in position, to cause the pressure of such surrounding air on said exposed surface to hold the joint-forming surface of the pad against said seating surface.

In testimony whereof I affix my signature in presence of two witnesses.

ASKIN MORRISON NICHOLAS.
